UNITED STATES PATENT OFFICE.

ADOLPHUS A. MCLEOD, OF CHERAW, SOUTH CAROLINA.

DESIGN FOR A PAN-HANDLE.

SPECIFICATION forming part of Design No. 21,614, dated June 7, 1892.

Application filed July 2, 1891. Serial No. 398,303. Term of patent 14 years.

To all whom it may concern:

Be it known that I, ADOLPHUS A. MCLEOD, a citizen of the United States, residing at Cheraw, in the county of Chesterfield and State of South Carolina, have invented and produced a new and original Design for Pan-Handles, of which the following is a description.

The drawing presents a perspective view of a pan-handle, showing my design.

The leading feature of my design consists in the configurations at B, b, C, and c, and the configuration of the body of the handle.

At one end of the representation A of the body of the handle are produced the representations C, which depart forwardly in about the line of the top surface of the body A, and diverge laterally, presenting to the eye, generally, the effect of a triangle, and at the ex-

tremities of said triangular representations are produced upwardly-extending vertical representations c. Beginning at about the intersection of the lines forming the triangular representation are the lines B, which extend downward from said intersecting lines and produce in connection therewith the effect of a right angle. The body of the handle gradually widens from the configurations B C, and then tapers off nearly to a point and presents the appearance of open-work, as shown.

I claim—

The design for a pan-handle, herein shown and described.

ADOLPHUS A. MCLEOD.
